(57) **CLAIM**

We claim the ornamental design for an extruded handle, as shown and described.

DESCRIPTION

FIG. 1 is a perspective view of the extruded handle according to an embodiment of the present invention in the environment of an appliance;

FIG. 2 is a perspective view of the extruded handle shown in FIG. 1;

FIG. 3 is an elevated front view of the extruded handle shown in FIG. 1;

FIG. 4 is an elevated rear view of the extruded handle shown in FIG. 1;

FIG. 5 is an elevated left side view of the extruded handle shown in FIG. 1;

FIG. 6 is an elevated right side view of the extruded handle shown in FIG. 1;

FIG. 7 is a top view of the extruded handle shown in FIG. 1; and,

FIG. 8 is a bottom view of the extruded handle shown in FIG. 1.

The broken lines in FIG. 1 show the environment of the claimed extruded handle. The broken lines in all of the Figures form no part of the claimed design.
